UNITED STATES PATENT OFFICE.

FRIEDRICH WILHELM FÖRSTER, OF BURLINGTON, IOWA.

FOOT-POWER HAMMER.

SPECIFICATION forming part of Letters Patent No. 644,589, dated March 6, 1900.

Application filed July 13, 1899. Serial No. 723,686. (No model.)

To all whom it may concern:

Be it known that I, FRIEDRICH WILHELM FÖRSTER, of Burlington, in the county of Des Moines and State of Iowa, have invented certain new and useful Improvements in Foot-Power Hammers; and I do hereby declare the following to be a full, clear, and exact description of the invention, such as will enable others skilled in the art to which it appertains to make and use the same.

My invention relates to an improvement in foot-power hammers; and it consists in certain novel features of construction and combinations of parts, as will be hereinafter more fully described, and pointed out in the claims.

In the accompanying drawings, Figure 1 represents a view of my invention in its operative position on an anvil. Fig. 2 is a similar view of the reverse side of the same, some 20 of the operating parts being broken away. Figs. 3 and 4 are views of detached parts.

V represents a base or support on which is suitably mounted an anvil A, which latter is preferably of the construction usually employed by blacksmiths. Removably secured on the prong of anvil A by the clips T T' are the two bent brackets K and L, between which the clamp for securing handle O of hammer or sledge R is pivotally mounted, as will be 25 more fully hereinafter described. This hammer-clamp is composed of two parallel sections or blocks B B' of suitable length, the former of which is rigidly secured within the two loops or straps C C, while the latter of 30 said sections or blocks is loosely mounted in said loops or straps and is adapted to be moved toward its mate or fellow by the set-screws P P, mounted in the screw-threaded openings in the upper ends of loops or straps C C. By 35 providing the adjacent faces of the parallel sections or blocks B B' with the V-shaped grooves, as shown in Fig. 3 of the drawings, a more rigid grip on handle O is secured, and all liability of the latter turning or twisting is 40 prevented.

Secured to the outer face of movable section B' and at a suitable point between its ends is a bearing E, in which is mounted a sleeve E', through which latter passes the axle 45 or fulerum E². Through the medium of this axle or fulerum E² the hammer-clamp, pre-

viously described, is pivotally supported between the bent brackets K and L, one end of said axle or fulerum having its seat in vertical slot K' of bracket K, while the opposite 55 end thereof has its seat in bearing S, located in the upper end of bracket L. Surrounding sleeve E' is a strap U, which is detachable by means of a set-screw U' for the purpose of enabling the hammer-carrying frame or clamp 60 to be shifted laterally when it is desirable to change the striking-point of the hammer.

Axle or fulerum E² is prevented from moving laterally by means of a pin passing through one end thereof at a point adjacent to its pivotal connection with bracket L, while its opposite or screw-threaded end is provided with a lever J, which latter rests against the outer face of bracket K, the lever having a threaded hole to receive the threaded end of axle E². 70

The treadle E³ has its fulerum on the base or support V at the point X and is connected to the hammer-carrying clamp at a point in advance of bracket L by a spring-pitman D through the medium of hook H, carried by 75 the upper member B' of the hammer-carrying frame.

The hammer-carrying frame is normally held in an elevated position by a spring F, the upper end of which is connected to the lower 80 end of rod G² by means of a chain G³, while its opposite end is connected to an eye carried by base or support V, as at W. The upper end of rod G is connected directly to the upper section or block B' of the hammer-clamp 85 by a hook G. This spring F not only performs the function above noted, but also returns the hammer-clamp and hammer supported therein to its normal position as soon as pressure in a downward direction is removed from treadle E³. 90

In actual operation the foot of the operator is placed upon the treadle E³ and forced downwardly, which throws the sledge or hammer down upon the anvil or on the tool N, as the 95 case may be, with more or less force, dependent upon the pressure applied and at the will of the operator.

When the device is used for rounding iron, or making a shoulder upon iron, or squaring iron, the position of the various parts is as 100 shown in the drawings. When, however, it

is desired to strike the sledge upon the surface of the anvil, as when sharpening a plow-share, the fulcrum-pin or axle E² is removed from its bearing S in bracket L by slightly 5 twisting the latter to one side and lowering said axle or fulcrum to a point opposite bearing S' in bracket L, after which bracket L is turned back to its proper position and the fulcrum-pin or axle fastened into said bearing S'. When the hammer-clamp is lowered as just described, the rods D and G² are detached from said hammer-clamp and shortened by rehooking them into the holes H' and G', respectively. The tension of spring F 10 may be regulated as desired by means of chain G³.

In cases where it is desirable to use the anvil without removing the striking mechanism therefrom the hook M is brought over the 15 bent bracket L, whereby the hammer will be held in a perpendicular position and against accidental displacement.

It is evident that changes in the construction and relative arrangement of the several 20 parts might be made without avoiding my invention. For instance, any suitable arrangement for supporting brackets K and L might be employed in lieu of support V and anvil A, and hence I would have it understood that 25 I do not restrict myself to the employment of the base and anvil shown nor do I wish to confine myself to the particular construction and arrangement of the remaining parts 30 shown and described; but,

35 Having fully described my invention, what I claim as new, and desire to secure by Letters Patent, is—

1. The combination with a bracket, of a 40 clamp for a hammer pivotally mounted in said bracket, and means for adjusting the

pivotal support of the clamp both vertically and laterally.

2. The combination with a bracket or standard comprising two members, of a clamp for a hammer disposed between the members of 45 the clamp or support, a pin passing through said members and pivotally connected with the clamp, means for adjusting the clamp laterally on said pin, and means for permitting a vertical adjustment of said pin. 50

3. The combination with a bracket or support comprising two members, and a clamp for a hammer disposed between the members of the bracket or support, of a sleeve mounted on the clamp, a plate for normally securing the sleeve to the clamp, means for releasing the sleeve from the plate to permit the adjustment of the sleeve, and a pin passing through the members of the bracket or support and said sleeve. 55

4. The combination with a bracket comprising two members and means at the lower end of said bracket for securing it to an anvil, of a clamp disposed between the members of the bracket and comprising two parallel elongated members for the reception of the handle of a hammer between them, a pin passing through the members of the bracket and pivotally supporting the clamp, means for vertically adjusting said pin and means 65 for effecting the lateral adjustment of the clamp on said pin. 70

In testimony whereof I have signed this specification in the presence of two subscribing witnesses.

FRIEDRICH WILHELM FÜRSTER.
